UNITED STATES PATENT OFFICE

ALFRED J. SCHMIDT, OF JERSEY CITY, NEW JERSEY, ASSIGNOR TO JOHN WANAMAKER, PHILADELPHIA, OF PHILADELPHIA, PENNSYLVANIA, A CORPORATION OF PENNSYLVANIA.

KNITTED GARMENT.

1,197,551.

Specification of Letters Patent. Patented Sept. 5, 1916.

Application filed March 31, 1915. Serial No. 18,350.

To all whom it may concern:

Be it known that I, ALFRED J. SCHMIDT, a subject of the German Emperor, and a resident of Jersey City, Hudson county, 5 New Jersey, have invented certain Improvements in Knitted Garments, of which the following is a specification.

My invention relates to knitted garments on which are displayed letters, numerals 10 and other devices, and the object of my invention is to apply such letters, numerals and the like by means of individual threads, substantially forming stitches, superposed upon certain individual stitches of the 15 fabric composing the garment, so that the representation of a clean-cut letter, emblem, numeral or the like may be effected and, in the case of knitted garments, will completely cover the underlying stitches, avoiding 20 grinning of the ground stitches through the overlaid stitches. The superposed threads will lie in the same direction as the stitches covered by the same, and as the superposed threads are limited in area to 25 the individual stitches over which they are applied, there will be no grinning between the rows of stitches should the garment be pulled adjacent the letter, numeral or other device applied thereto. These and other 30 features of my invention are more fully described hereinafter, reference being had to the accompanying drawings, in which:

Figure 1, is an enlarged face view of a section of a sweater or similar garment showing the manner of applying a letter or numeral constituting the subject of my invention; Fig. 2, is a sectional view on the line 2—2, Fig. 1, showing an interlining or covering for the underside of the garment at 40 the point where the letter, numeral &c., is applied, and Fig. 3, is a perspective view of a sweater garment showing the front thrown back to expose the inside of the garment at the point where the letter or numeral is applied and the interlining or covering for 45 the back of such letter, numeral, or the like.

The usual practice heretofore of displaying letters, numerals, &c., upon knitted garments such as sweaters, sweater coats, shirts and the like has been to sew a patch on the front of the garment carrying such letter or figure, or the patch may be in the shape of the letter, numeral or figure. This is objectionable in many ways. In the first

place, it is difficult to center the letter properly as it is usually of a material wholly different from the body of the sweater; it is not pleasing in appearance; the stitches securing it in place show on the underside of the sweater, and it is not permanent, 55 since the stitches securing it to the garment are liable to wear or work loose, and it destroys the elasticity of the garment at the point where it is applied to the same. In my improved garment, however, the individual stitches composing the same are overlaid with threads of a yarn identical with that composing the garment as to weight and general characteristics but of a different color, and the overlaid stitches follow identically 65 the stitches and wales of stitches composing the body of the garment without destroying or in any way altering the elasticity of the same. It is a relatively simple matter to work out a letter of proper 70 size by using the stitches making up the fabric of the garment as the means of defining the same, and in the accompanying drawings, the representation of the letter "U" has been so effected. These stitches may 75 be applied in various ways, but are preferably set by hand to insure proper covering of the underlying interlocked stitches constituting the body of the garment, and such superposed stitches will, of course, have to 80 be secured to and tied into the back of the garment in a manner that will avoid showing the same upon the face of the garment or of grinning through small apertures that might present themselves when the garment 85 is pulled or stretched. Such tying in of the superposed threads would naturally present an unsightly rear surface, and this rear surface is covered with a patch of knitted material of the same shade or color as the garment, which patch has its back surface faced to agree or coincide with the back surface of the garment; the rear portions of the stitches of the same lying in the same 90 position as the rear portions of the stitches 95 of the garment, and this patch is sewn down by blind stitching to the rear face of the sweater or garment, as clearly shown in Fig. 3. The patch being of the same color, a plain one-tone surface is presented, in which 100 the securing means are scarcely discernible since the stitches of the patch extend in the same direction as the stitches of the rear

face of the garment. This patch, furthermore, does not destroy nor affect the elasticity of that portion of the garment to which it is attached.

5 In the drawings, 1 represents the material of the garment; 2 the individual stitches of the same; 3 the overlaid or superposed stitches of a contrasting color; 4 the patch secured on the under face of the garment to 10 hide the rear portions of the superposed stitches, and 5 indicates the blind stitching securing such patch in place.

15 The display of letters, numerals or the like on the outer surface of a sweater or similar garment is in the nature of ornamentation, and to avoid the use of alternative expressions this term has been employed in the 20 claims. It will be understood, however, that the term "ornamentation" is intended to cover and include letters, numerals, figures, symbols, or the like when displayed in the manner above described.

I claim:

25 1. A garment of the sweater type made of knitted fabric comprising a plurality of interconnected stitches, said garment having ornamentation upon the outer surface of the same formed by stitches of the same character as those making up the garment but 30 of a different color, each stitch of ornamentation being coextensive in area with a stitch of the fabric, the superposed stitches

being tied into the fabric adjacent the wales upon which they are placed.

2. A knitted garment having ornamentation formed on the face of the same by superposing upon the stitches constituting the garment a thread of a different color, said overlaid thread being isolated with respect to the stitches carrying the same, and 40 a patch carried by the rear face of said garment for covering the portions of the superposed or overlaid threads, said patch being of the same material as the garment and having 45 stitches lying in the same plane as the stitches of the garment so as to simulate the plain rear surface of the latter.

3. A knitted garment having ornamentation formed on the face of the same by superposing upon the stitches constituting the garment a thread of a different color, said overlaid thread being isolated with respect to the stitches carrying the same and tied in at the back of the same along the 50 wales of the covered stitches, and a patch carried by the rear face of said garment for covering the portions of the superposed or overlaid threads, said patch being of the same knitted material and color as the garment and having its back stitches lying in 55 the same plane or relation as the stitches of the garment so as to simulate the plain rear surface of the latter.

ALFRED J. SCHMIDT.
